(57) CLAIM

The ornamental design for a ruffled sock, as shown and described.

DESCRIPTION

FIG. 1 is a front elevational view of a ruffled sock showing my new design;

FIG. 2 is a rear elevational view thereof;

FIG. 3 is a right side elevational view thereof;

FIG. 4 is a top plan view thereof; and,

FIG. 5 is a bottom plan view thereof.

side view with the exception of the bow.
